UNITED STATES PATENT OFFICE.

WILLIAM J. SHINN, OF HERMITAGE, MISSOURI.

GATE.

SPECIFICATION forming part of Letters Patent No. 430,220, dated June 17, 1890.

Application filed January 17, 1890. Serial No. 337,239. (No model.)

To all whom it may concern:

Be it known that I, WILLIAM J. SHINN, a citizen of the United States, residing at Hermitage, in the county of Hickory and State 5 of Missouri, have invented a new and useful Gate, of which the following is a specification.

The invention relates to improvements in gates.

The object of the present invention is to 10 provide a lever-opening gate of simple and inexpensive construction, adapted to be readily opened without the necessity of dismounting from a horse or vehicle, and capable of remaining open until the person has passed 15 through and of being automatically latched.

The invention consists in the construction and novel combination and arrangement of parts hereinafter fully described, illustrated in the accompanying drawings, and pointed 20 out in the claims hereto appended.

In the drawings, Figure 1 is a perspective view of a gate constructed in accordance with this invention. Fig. 2 is a side elevation of 25 the gate. Fig. 3 is a transverse sectional view. Fig. 4 is a detail view of the movable frame and the operating-rod that controls the latches.

Referring to the accompanying drawings, 1 designates a gate, which is hinged to a post 30 2, and has its top bar 3 extending rearward and forming a projection 4, upon which is mounted a movable frame 5, composed of the bars 6 and 7, which are arranged at an angle and have their outer ends secured together 35 and pivotally connected to an operating-rod 8, that controls latches 9 and 10. The bar 7 is pivoted to the rearward extension of the top bar 4 by a pin 11, which extends downward and forms the upper pintle of the gate 40 and engages an eye of the hinged post 2, and is supported by a staple. The other bar 6 of the frame is provided with a longitudinal slot 13, which is engaged by a pin 14, that projects from the top of the rearward extension 4 of 45 the gate and limits the motion or the movement of the frame 5. The rod 8 is provided at its opposite end with a recess 15, in which are arranged the short arms 16 and 17 of the latches 9 and 10, and the said arms 16 and 17 50 are adapted to be engaged, respectively, by the rear and front walls of the recess 15 of the operating-rod 8 to release the gate and

allow the same to be opened or closed after being locked in its open position.

The gate is operated by rods 18 and 19, 55 whose adjacent ends are pivoted to the movable frame at the point where the bars 6 and 7 cross each other, and the said rods are supported by posts 20 and 21, whose upper ends are bifurcated and provided with rollers 22, 60 that enable the rods to move easily.

The latch-post 23 is provided with a keeper 24, whose recess is arranged to be engaged by the lower latch 10 when the gate is closed, and the supporting-post 21 is provided with 65 a similar keeper 25, whose recess is arranged to be engaged by the upper latch 9 to retain the gate in its open position and prevent its closing until after the person has passed through. When the gate is closed, and one 70 of the rods 18 or 19 is moved to open the gate, the movable frame 5 swings on its pivot 11 the length of the slot 13, which distance is sufficient to bring the front wall of the recess 15 into engagement with the short arm 17 of 75 the lower latch 10 and raise the latter from engagement with the keeper 24 of the latch-post and release the gate and allow the latter to be opened. The gate swings open and the upper latch 9 engages the keeper 25 of the 80 supporting-post 21 and the gate is locked in its open position, and is held there until the person has passed through, and then one of the rods 18 or 19 is again moved, which operates the rod 8 and brings the rear wall 85 of the recess 15 into engagement with the short arm 16 of the upper latch 9, and raises the latter from the keeper 25 and allows the gate to swing to and bring the lower latch again into engagement with the keeper of the 90 latch-post 24 to lock the gate. The hinge-post 2 is braced by a beam 26, that extends rearward therefrom, and by a beam 27, that connects the hinge-post to the supporting-post 20 and prevents the gate sagging. 95

The gate may be of any desirable construction, and is provided with a guard-wire 28, that extends from the pivot of the lower latch to the keeper 24 and prevents the gate from being accidentally opened by cattle rubbing 100 against it.

It will readily be seen that the gate is simple and inexpensive in its construction, adapted to be readily opened and closed, and capable

of being automatically latched to retain it in its open and closed positions.

Having thus described my invention, I claim—

5 1. The combination of the gate, the upper and lower latches secured to the gate, the operating-rod 8, arranged to engage the latches alternately, and the movable frame pivoted to the gate and the operating-rod and adapted 10 to be moved on its pivot when the gate is opened and closed, substantially as and for the purpose described.

2. The combination of the gate, the upper and lower latches, the frame 5, pivoted to the 15 gate and capable of limited movement, the operating-rod 8, pivoted to the frame and arranged between and alternately operating the latches, and the rods pivoted to the frame and adapted to open and close the gate, substantially as described.

3. The combination of the gate, the upper and lower latches secured to the gate, the frame 5, composed of the bars 6 and 7, pivoted to the gate and provided with a longitudinal 20 slot 13, adapted to limit the movement of the frame, the rod 8, pivoted to the frame 5 and provided with the recess 15, arranged to engage with the latches alternately, and the

rods 18 and 19, secured to the frame 5 and adapted to operate the gate, substantially as 30 described.

4. The combination of the gate, the upper and lower latches secured to the gate, and the rod 8, arranged between the latches and adapted alternately to operate the same, substantially as and for the purpose described. 35

5. The combination of the gate, the upper and lower latches secured to the gate, the frame 5, composed of the bars 6 and 7, pivoted to the gate and provided with a longitudinal 40 slot 13, adapted to limit the movement of the frame, the rod 8, pivoted to the frame 5 and provided with the recess 15, arranged to engage the latches alternately, the rods 18 and 19, secured to the frame 5 and adapted to 45 operate the gate, and the posts 20 and 21, having bifurcated upper ends with rollers 22, the rods 18 and 19 fitting in the bifurcated ends and resting on the rollers, as set forth.

In testimony that I claim the foregoing as 50 my own I have hereto affixed my signature in presence of two witnesses.

WILLIAM J. SHINN.
